No. 704,561.

Patented July 15, 1902.

K. C. MOORE.

CLOTHES DRIER.

(Application filed Jan. 8, 1901.)

(No Model.)

UNITED STATES PATENT OFFICE.

KINGMAN COLQUITT MOORE, OF MACON, GEORGIA.

CLOTHES-DRIER.

SPECIFICATION forming part of Letters Patent No. 704,561, dated July 15, 1902.

Application filed January 3, 1901. Serial No. 41,951. (No model.)

To all whom it may concern:

Be it known that I, KINGMAN COLQUITT MOORE, a citizen of the United States, residing at Macon, in the county of Bibb and State 5 of Georgia, have invented certain new and useful Improvements in Clothes-Driers; and I do hereby declare the following to be a full, clear, and exact description of the invention, such as will enable others skilled in the art to 10 which it appertains to make and use the same.

This invention relates to driers for clothes and other articles, substantially as will hereinafter be more particularly described.

The object of my invention is to provide a 15 simple, inexpensive, and light but strong and durable device of this character adapted for convenient attachment to a support, preferably to the outside of a window, so that beds or mattresses, clothing, and other articles may 20 be supported thereon for the purpose of airing, sunning, or drying the same, and, further, to provide a foldable device adapted to be folded in compact form when detached, so as to occupy a minimum of space for shipment or storage. It may be stated that the 25 said device is further intended for the use of persons residing in upper stories or flats of buildings, where yard-space is either very limited or not to be had at all, to say nothing of 30 the inconvenience of descending to a yard or ascending to the roof of a house for the purpose of airing or drying clothes and other articles. When not in use, the device can be readily lifted from its support and stowed 35 away in a room and then with equal facility be again suspended in position for use with the expenditure of very little strength upon the part of the person using the same.

In one embodiment my invention may consist of a single foldable supporting-frame 40 adapted for attachment to the outside of a window or other suitable support in the manner of a shelf or scaffold, and in another embodiment the invention may comprise, in addition to 45 and in connection with said supporting-frame, an extra or auxiliary frame in the nature of a clothes-rack attachment adapted to be secured to said first-mentioned frame.

The invention will first be hereinafter more 50 particularly described with reference to the accompanying drawings, which form a part

of this specification, and then pointed out in the claims at the end of the description.

In said drawings, in which similar parts in the different views are denoted by like letters of reference, Figure 1 is a perspective view 55 of a bed and clothes drying and airing device embodying my invention, the same being represented as secured to the outside of a window. Fig. 2 is a similar view showing the auxiliary frame or rack attachment secured to the frame represented in Fig. 1. Fig. 3 is a detail view in perspective of one of the brackets or angle-irons fitted to said clothes drying and airing device for attachment to 60 the supporting cables or wires and to the connecting-irons of the said auxiliary frame or rack attachment when the latter is employed, and Fig. 4 is a front view of said bracket. Figs. 5 and 6 are detail perspective views of 65 one of the connecting irons or castings of the said auxiliary frame or rack attachment and one of the devices employed for securing the inner ends of the clothes-drier to the window-sill, respectively. Fig. 7 is a front elevation 70 of the device, including both the main frame and the auxiliary frame detached and folded, illustrating the manner of placing them together, so as to occupy a minimum of space for shipment or storage; and Fig. 8 is a detail 75 fragmentary view in perspective of a portion of the device, illustrating the manner of folding the same.

A device embodying my invention, which is represented in Figs. 1 and 2 of the drawings as attached to the window-frame of a building, may consist of a pair of parallel rods or bars A A and a foldable cross-bar B, hinged to each of said rods or bars A A at a point intermediate their length in a manner 80 presently to be described, the inner ends of said rods A A being adapted to be rigidly secured to the window-sill and the outer ends to be properly supported by suitable ropes or cables, preferably stout wires C C, secured to 85 the sides of the window-frame by hooks c c or in any suitable manner. The said cross-bar B preferably comprises two equal parts or pieces hinged at their adjacent ends, as at b, in such manner as to be foldable upon each 90 other in a plane at right angles to the plane of said bars A A and preferably foldable in 95 100

- one direction only, each of said parts or pieces being also hinged at the other end to one of the said rods A, as at b', in such manner as to be foldable thereupon in a plane coincident 5 with the plane of said parallel rods A and preferably foldable in one direction only and each piece in the same direction. By this construction when the frame or device is attached to the window in the manner described 10 the said cross-bar serves to effectually brace or separate the said rods A, and the frame is rendered perfectly rigid as well as non-collapsible, while when detached the frame or device may be folded together or upon itself, 15 so as to bring the said rods A together in the manner illustrated in Fig. 8, whereupon the folded or doubled cross-bar B or parts thereof may be further folded in the direction indicated by the arrow, Fig. 8, upon the said rods 20 A to reduce the device to the compact form illustrated in the upper part of Fig. 7. To further insure against collapsibility of the frame when in use for the purposes mentioned, I employ a suitable sleeve or collar b², slidably fitted around the said cross-rod B and adapted to close over the junction of the two parts thereof to render the rod rigid in use and adapted to be moved off from said junction to permit folding of the frame, the movement 25 of said sleeve b² being properly limited by means of a suitable pin or stop b³ on one member or part of said foldable cross-bar or other suitable means to prevent said sleeve from falling to a position to interfere with the 30 folding of the frame. (See Fig. 8.)
- To properly secure the inner ends of the rods A to the window-frame, I may employ such devices as are shown in detail in Fig. 6, consisting, preferably, of flat irons or castings 35 D, adapted to be secured to the window-sill and provided with suitable screw-holes d for this purpose, each of said irons having a forward collar or sleeve d' formed integral therewith to receive the inner end of one of the 40 said rods A and a rearward upstanding lug or projection d² to prevent said rod from slipping back into the window, and set-screws d³ may also be provided in suitable screw-holes d⁴ in said collars d', the same being 45 adapted to be screwed against the rods A to hold them fast. However, in place of the irons D other devices, such as ordinary staples, may be employed, or the rods may be secured to the window-sill in any proper 50 manner.
- To the outer end of each of the rods A of the frame is preferably secured a suitable bracket or angle-iron E, having its upstanding portion or arm e positioned at the extremity 55 of said rod, and to the upper eyed or looped extremities e' of the upstanding arms e are fastened the supporting-wires C, the said wires being thus attached to the frame in such manner and position as to permit 60 utilizing its whole length for supporting mattresses or other articles thereon without ob-

struction thereto by the wires, which, however, may be otherwise secured to the frame, if desired. Each of said brackets E is preferably provided with a bottom socket e², in which the outer end of one of the rods A is fitted and secured, all liability of the brackets working loose and becoming detached from the rods being thus obviated. Along the front or outer face of each bracket is formed a flaring or T-shaped rib or projection e³, increasing in size toward its lower end, the said ribs being designed for engagement with correspondingly-shaped grooves or sleeves on the auxiliary frame when the latter is attached to the frame above described, as hereinafter explained. Said brackets are also provided with rearward lugs or hooks e⁴, adapted to engage and hold the first of a series of connected slats F, (shown partly in Figs. 1 and 2,) which may be laid on the supporting-frame when desired. When the frame is pushed out from the window to be attached thereto, the first of said slats may be first placed before the lugs or hooks e⁴, so that the slats will be drawn out with the frame, and after the frame is in place the last or rearward slat may be slipped over suitable hooks f on the rearward portions of the rods A, and the said hooks f, which are here shown pointing away from the window, may then be turned toward the window to secure the said slat.

As before stated, I may employ in conjunction with the device or frame already described an auxiliary frame in the nature of a clothes-rack attachment, the same being illustrated in Fig. 2 as attached to the main frame and in Fig. 7 as folded and placed alongside the main frame. Said auxiliary device or frame consists of a pair of parallel rods or bars G G and a pair of parallel and foldable cross bars or rods H H, hinged to and connecting the same, the said cross-bars H being preferably the same distance apart as the bars or rods A of the main frame. Each of the said cross-bars H preferably comprises two equal parts or portions hinged together at their adjacent ends h in exactly the same manner as the cross-bar B and also hinged to the parallel rods or bars G, as at h', in the same manner as the cross-bar B to the parallel rods A, the two cross-bars H, however, being preferably made foldable upon the bars or rods G only toward the ends of the latter or away from each other, for a reason which shall hereinafter appear. Hence said auxiliary frame when not in use may be folded upon itself to bring the rods G together, whereupon the folded or doubled cross-bars H may then be further folded upon the said rods G (in opposite directions or away from each other) to reduce the auxiliary frame to the compact form illustrated in the lower part of Fig. 7 in exactly the same manner as the main frame. The auxiliary frame is also rendered non-collapsible in use by means of

sleeves or collars h^2 on the bars H, similar to that employed on the cross-bar B, said collars being supported in proper place over the junction of the said foldable bars H by suitable pins or stops h^3 on the portions beneath said junctions, or said collars may be secured in place by set-screws entered therethrough or by other suitable means.

To provide for attachment of the auxiliary frame or rack to the main frame, the cross-bars H of the former are each provided with a suitable connecting device I, (shown in detail in Fig. 5,) having a collar or band i fitting around and rigidly secured to said bar and having a groove or sleeve i' on one side corresponding in shape with the flaring or T-shaped ribs e^3 on the brackets E and adapted to slide down over the latter, whereby the auxiliary frame may be quickly and conveniently attached to or detached from the main frame by simply sliding the sleeves or grooves i' down over or up from the said ribs e^3 . The downwardly-increasing form of the ribs e^3 and the corresponding shape of the grooves or sleeves i' serve to maintain the auxiliary frame in proper position, as will be well understood.

To each end of the bars G of the auxiliary frame suitable fastening devices, such as eyes g , may be inserted to provide attachments for ropes or wires J, which may be stretched from suitable points of the window-frame to serve as clothes-lines, and of course suitable fastenings may be provided elsewhere for the same purpose, if desired.

The manner of using the device will be apparent from the foregoing description. The supporting-wires being properly attached to the main frame, the latter may be readily pushed out from the window, with or without the slats F, as preferred, and the inner ends of the rods A brought into proper position in the sleeve d' and the free ends of the wires connected to the window, while if the auxiliary frame is also to be used said frame can be placed outside the window and attached to the main frame in the manner before indicated before the latter is pushed out to its full distance. For shipment or storage the frame may be easily folded and placed together in the manner illustrated in Fig. 7, with the folded cross-bar B positioned between the folded cross-bars H, so as to occupy a minimum of space. The device thus described is very efficient and convenient, simple in construction, inexpensive in manufacture, and adapted to be constructed to combine lightness with strength and durability.

It will be understood that the invention is susceptible of various modifications without departing from its scope. Thus the main frame may be provided with two cross-bars similarly to the auxiliary frame, though one cross-bar is sufficient, the inner ends of the rods A of the main frame being braced at the window-sill.

While the connecting devices E and I and

other similar parts are preferably formed of metal for the purposes of strength and durability, the same may, however, be formed of any suitable material.

Having thus fully described my invention, what I claim as new, and desire to secure by Letters Patent of the United States, is—

1. In a clothes-drying frame of the character described, parallel rods or bars, and a foldable cross-bar, the latter comprising two parts of substantially equal length hinged at adjacent ends and foldable lengthwise upon each other in a plane at right angles to said parallel rods, said cross-bar being also hinged at opposite ends to the parallel rods and foldable lengthwise thereagainst in one direction only in a plane coincident with the latter, and means for preventing folding of said frame when in use, substantially as described. 75

2. In a clothes-drying frame of the character described, parallel rods or bars, and a foldable cross-bar comprising two parts of substantially equal length hinged at adjacent ends and foldable lengthwise upon each other in one direction only and in a plane perpendicular to said parallel rods, said cross-bar being also hinged at opposite ends to the two parallel rods and foldable lengthwise against each one thereof in a direction toward one 90 end of the frame only and in a plane parallel with said rods; substantially as described.

3. In a device of the character described, the main frame in the nature of a window shelf or scaffold in combination with the auxiliary frame or rack attachment therefor, one of said frames being provided with outwardly-flaring and downwardly-increasing vertical ribs or projections and the other frame with correspondingly-shaped grooves adapted to fit and slide over said ribs, whereby said auxiliary frame may be readily attached to and detached from said main frame; substantially as described. 100

4. In combination with the main frame or window-scaffold, consisting of a pair of parallel rods or bars and a cross-bar, said parallel bars having brackets fitted to their outer or forward ends and provided with vertical outwardly-flaring and downwardly-increasing ribs, the auxiliary frame or rack consisting of a pair of parallel rods and a pair of parallel cross-bars, the latter being about the same distance apart as the parallel rods of the main frame and having secured to their sides sleeves corresponding in shape and adapted to slide down over the said ribs on the brackets of the main frame, whereby said auxiliary frame may be readily attached or detached; substantially as described. 115

5. In a device of the character described, a pair of parallel rods, and a cross-bar connecting the same, each of said parallel rods being provided at its outer end with a bracket having a socket in which said rod is fitted 120 and having an upstanding arm at the extremity of said rod provided at its upper ex-

tremity with an eye for the fastening-wire, said brackets having also rearward hooks or lugs adjacent the rods, substantially as and for the purposes described.

5 6. A clothes-drier adapted for attachment to a support, and constructed of collapsible bars and a suspensory device, in combination with an auxiliary collapsible frame detach-

ably mounted upright upon said collapsible bars; substantially as described. 15

In testimony whereof I affix my signature in presence of two witnesses.

KINGMAN COLQUITT MOORE.
